James Basso, Jr.

By *Orff & Meekigan* Attorney

UNITED STATES PATENT OFFICE.

JAMES BASSO, JR., OF PANAMA, ILLINOIS.

STEAM HEATER FOR AUTOMOBILES.

Application filed September 20, 1921. Serial No. 501,877.

To all whom it may concern:

Be it known that I, JAMES BASSO, Jr., a citizen of the United States, residing at Panama, in the county of Montgomery and State 5 of Illinois, have invented certain new and useful Improvements in a Steam Heater for Automobiles, of which the following is a specification.

This invention relates to apparatus for 10 heating automobiles and more particularly to a steam heater adapted to be placed in the body of the automobile and connected, by suitable piping, to the water jacket of one of the cylinders in a manner that will permit 15 the generation of steam to be conducted through the piping to the heater.

One of the objects of the invention is to 20 provide an apparatus of this character which will have a novel arrangement to cause the automatic formation of steam in one of the cylinders of the motor so that a predetermined quantity of water will be maintained in the water jacket while steam is being generated.

25 Other objects of the invention will appear upon consideration of the following detail description and accompanying drawings, wherein:—

Figure 1 is a fragmentary view of an automobile motor, partly in section, showing 30 the invention applied thereto,

Figure 2 is a detail view of the manner of connecting the steam pipes to the source of steam supply, and

35 Figure 3 is a view of an automatic valve employed in connection with the operation of the apparatus.

Referring to the drawing by numerals, the automobile motor 1 having the four cylinders is of the conventional type and each cylinder is provided with the usual water jacket through which the water circulates for the purpose of cooling the motor. The water jackets for the cylinders A, B and C 40 are in communication with each other so that the water flowing from the radiator will pass through the intake pipe 2 and be conducted through the connecting pipe 3 through the space between the two cylinders B and C so that water is supplied to the water jacket. The fourth cylinder D, however, 45 has its water jacket 4 separated from the other water jacket by a dividing wall, a portion of which is indicated at 5 in Fig. 1. A branch pipe 6 leads from the intake pipe and is extended upwardly to the water jacket 4,

and this branch pipe is provided with a valve 7 having an operating stem 8 which is connected to an operating rod 9 projecting rearwardly to a point within convenient reach 60 of the operator of the vehicle so that the handle 10 on the end of the operating rod 9 may be grasped by the operator to open or close the valve 7 whereby the water may be conducted to or shut off from the water 65 jacket 4.

The dividing wall 5 which separates the water jacket 4 from the other water jacket of the motor is provided with a restricted opening which is small enough to permit 70 only a relatively small quantity of water to pass through when the opening is opened as indicated at 11. A valve seat 12 is formed in this opening, and this valve seat is adapted to be engaged by a valve disk 13 mounted 75 upon a valve stem 14 which is slidably mounted in a bracket 15 whereby the valve stem may be vertically raised or lowered. The lower end of the valve stem 14 is provided with a float 16 which floats upon the 80 water in the water jacket 4. When the valve disk 13 is seated in the valve seat 12 the restricted opening 11 will be closed and, when the valve disk 13 is lowered as shown in Fig. 1, water will be permitted to pass into the 85 water jacket 4.

A hand plate 17 is removably mounted on the end of the water jacket 4 to normally close a relatively large opening 18 which is arranged to permit access to the 90 automatic float valve. The plate 17 is provided with connections for steam pipes 19 which lead to radiators, one of which is indicated at 20. This radiator is of any 95 preferred type which will radiate heat when a quantity of steam is passed into the heater through the steam pipe.

The operation of the apparatus is as follows:

When the water passes from the radiator 100 through the intake pipe 3 it is conducted into the water jacket of the first three cylinders A, B and C through the pipe 3 in the usual manner, so that water from the radiator is always supplied to these three 105 water jackets. When the valve 7 is opened, water will be readily conducted to the water jacket 4 through the branch pipe 6 and, of course, the float 16 will rise to close the opening 11 and the parts will remain in 110 this position when it is not desired to supply heat to the heaters. When the valve 7

is closed, however, no water will pass through the branch pipe 6, but a small quantity of water will be permitted to pass through the restricted opening 11 by virtue 5 of the position of the valve 13 which will remain in open position as long as the water level is relatively low in the water jacket 4. This comparatively small quantity of water in the water jacket 4 will, 10 cause the water to be quickly heated from the heat generated by the action of the piston in the cylinder D and the steam rising from the water in the water jacket 4 will pass through the steam pipes 19 into 15 the heaters 20 and thus heat the body of the vehicle.

As the water rises, the float 16 will cause the valve 13 to close the opening 11 and it will remain in this position until enough 20 steam has been generated to cause the water to drop to a lower level whereupon an additional small quantity of water will be allowed to pass through the opening 11 and this will continue as long as it is desired 25 to generate steam in the water jacket 4 to be conducted to the heaters. Thus it will be seen that the action of the apparatus is entirely automatic after the valve 7 has been closed and sufficient steam may be generated to heat the interior of an ordinary 30 automobile body.

Minor changes may be made in the details of construction without departing from the spirit of the invention or the scope of the 35 claims hereunto appended.

What is claimed is:—

1. In combination with a motor for automobiles having cylinders and water jackets for the cylinders, one of the water jackets 40 being out of communication with the other water jacket with the exception of a restricted passageway, a float actuated valve in the said separated water jacket, the said valve being adapted to automatically rise 45 and fall with the varying water level in the

water jacket to close or open the said restricted passage-way, a radiator, pipes leading from the said water jacket to the radiator, and means to cut off the main supply of water from the said separated water 50 jacket.

2. In combination with a motor for automobiles having cylinders and water jackets for the cylinders, a dividing wall separating one of the water jackets from the other water jacket, a restricted opening in the said dividing wall, a valve for opening and closing the said opening in the dividing wall, a float attached to the valve for moving the valve with the varying levels of 60 water in the said divided water jacket, a water pipe leading to the divided water jacket, valve means in the said pipe to be manually operated for cutting off the supply of water from the radiator to the said 65 divided water jacket, a radiator in the automobile body, and steam pipes leading from the said divided water jacket to the said radiator.

3. In combination with an automobile motor having cylinders and water jackets for the cylinders, and a pipe for supplying water to the water jackets, one of the said water jackets being separated from the other water jacket by a dividing wall, said dividing wall having an opening, a branch pipe leading from the main water pipe to the said divided water jacket, a valve in the said branch pipe to be manually operated for opening or closing the said branch pipe, 70 a valve including a valve disk for closing the said opening in the dividing wall, a float member attached to the said valve disk, means for holding the valve in position for vertical movement when the water level 75 changes in the divided water jacket, and a radiator connected to the said divided water jacket.

In testimony whereof I affix my signature.

JAMES BASSO, JR.
